UNITED STATES PATENT OFFICE.

JOHN RUFF GLADNEY, OF VELASCO, TEXAS.

QUILTING-FRAME.

1,186,570.

Specification of Letters Patent. Patented June 13, 1916.

Application filed December 14, 1915. Serial No. 68,737.

To all whom it may concern:

Be it known that I, JOHN RUFF GLADNEY, a citizen of the United States, residing at Velasco, in the county of Brazoria, State of Texas, have invented a new and useful Quilting-Frame; and I do hereby declare the following to be a full, clear, and exact description of the invention, such as will enable others skilled in the art to which it appertains to make and use the same.

The present invention relates to certain new and useful improvements in quilting frames, and has for its object to provide a device of this character which embodies novel features of construction whereby the quilt can be conveniently handled and readily brought into position for either machine or hand quilting.

Further objects of the invention are to provide a quilting frame which is simple and inexpensive in its construction, which is suspended from a trolley and can be readily moved from place to place, which can be set at different heights, and which can be advantageously used for either machine or hand quilting.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a trolley quilting frame constructed in accordance with the invention. Fig. 2 is a top plan view thereof. Fig. 3 is an end elevation thereof, portions being broken away and shown in section. Fig. 4 is a transverse sectional view through the frame, showing the same as modified to form a cradle or crib.

Corresponding and like parts are referred to in the following description and indicated in all the views of the drawing by the same reference characters.

Specifically describing the present embodiment of the invention, the reference characters A designate a pair of similar and opposed end frames which have a spaced and parallel relation to each other when the quilting frame is in operation, and are provided at their lower ends with the roller carrying bars 1. The end frames A have

substantially the same shape as the letter A, being each formed of a pair of upwardly converging uprights 2 which are connected at an intermediate point by a cross bar 3, 60 and at their upper ends by the plates 4 which are applied to opposite sides of the uprights. It will also be observed that the upper ends of the uprights 2 are beveled and have a spaced and parallel relation to 65 each other, coöperating with the side plates 4 to provide a channel or guideway for the reception of a hanger 5. The upper end of the hanger 5 is square or rectangular in cross section so as to be held against rotation within the guide channel at the top of the end frame A, although the lower end of the hanger is substantially circular in cross section and loosely received within openings 6 and 7 in the cross bar 3 and 70 roller supporting bar 1 respectively. A set screw 8 in one of the plates 4 serves to engage the hanger 5 for the purpose of locking the same in an adjusted position. The upper end of the hanger 5 is fitted with a 75 looped plate 9 within which a grooved wheel 10 is mounted. The two end frames A are duplicates of each other, being each provided with an adjustably mounted hanger 5 and the trolley wheels 10 of the two 80 hangers are adapted to engage an overhead cable or wire 11 suitably stretched across the top of the room. The plates 4 are slightly spaced from the upper ends of the uprights 2, thereby providing a space within 85 which the looped plates 9 and trolley wheels 10 can be drawn and housed when the device is not in use.

The lower extremities of the uprights 2 are bifurcated, as indicated at 2^a, and the roller supporting bars 1 are reduced at one end, as indicated at 1^a, as well as at a point spaced from the opposite end, as indicated at 1^b. The reduced end portion 1^a of each of the bars is inserted within the lower end 90 of one of the uprights 2 and engaged by a pivot pin 12, while the reduced portion 1^b is received within the bifurcated end 2^a of the opposite upright 2 and secured in position therein by a locking pin 13. The portion of each of the bars 1 between the lower ends of the uprights 2 is provided with a pair of openings 14, while the projecting end of each of the bars is provided 95 with a pair of openings 15.

The rollers 16 are each provided at the ends thereof with trunnions or stems 16^a of

2
a size to engage any of the openings 14 and 15. For machine work the trunnions 16^a are placed in engagement with the openings 14 of the roller supporting bars 1, while for 5 hand quilting one of the rollers would be mounted within a set of the end openings 15, thereby presenting a larger area for quilting. The quilt or material being operated upon may be tacked upon one of 10 the rollers and wound upon the opposite roller as the work proceeds, or unwound from one roller and wound upon the other roller. When necessary, for purposes of adjustment, the two locking pins 13 can be 15 withdrawn and the bars 1 swung downwardly and upwardly on the opposite side of the frame about the pins 12 as pivots. After the desired adjustment has been 20 made the bars 1 can be swung back to their original positions and the locking pins 13 replaced.

The rollers 16 are shown as provided at points adjacent the ends thereof with keepers 17 which are suitably arranged for 25 engagement with locking hooks 18 on the bars 1. When these hooks 18 are caused to engage the keepers 17 the end frames A are locked to the rollers so that they can not swing away therefrom. The entire quilting 30 frame can be moved back and forth upon the overhead cable 11, and by adjusting the hangers 5 within the end frames A the quilting frame can be set at the desired elevation.

35 The device is also adapted to be converted into a cradle. For this purpose the rollers 16 are removed and replaced by side bars 19 provided with upwardly extending skeleton frames 20, said frames inclining 40 outwardly and resting against rods 21 inserted within openings 22 in the end frames A. Transversely disposed slats 23 are then placed upon the side bars 19, said slats 45 operating with the skeleton side frames 20 and the end frames A to provide a cradle.

Having thus described the invention, what I claim as new and desire to secure by Letters Patent, is:—

1. A quilting frame, including an overhead supporting cable, A-shaped skeleton end frames having vertical openings in the apexes thereof and corresponding openings in the cross bars, hangers slidable through

the vertical guideways and openings of the cross bars, means for locking the hangers 55 in an adjusted position, trolley wheels upon the hangers for engaging the overhead cable, roller supporting bars at the lower ends of the A-shaped end frames, and quilting rollers journaled between the roller supporting bars.

2. A quilting frame, including an overhead supporting cable, A-shaped skeleton end frames having polygonal vertically disposed guideways at the apexes thereof and 65 provided with corresponding circular openings in the cross bars, hangers slidably mounted within the guideways and openings and having polygonal upper ends which interlock with the polygonal guideways to normally hold the hangers against 70 rotation, means for locking the hangers in an adjusted position, trolley wheels upon the hangers for engaging the overhead cable, roller supporting bars at the lower 75 ends of the end frames, and quilting rollers journaled between the roller supporting bars.

3. A quilting frame including a pair of substantially A-shaped skeleton frames, an 80 overhead supporting cable, hangers slideable upon the end frames, means for locking the hangers in an adjusted position, trolley wheels upon the hangers for engaging the overhead cable, a roller supporting 85 bar at the bottom of each of the end frames, one end of each of the roller supporting bars being hingedly connected to one arm of the A-shaped frame and detachably connected at a point spaced from the opposite 90 end of the other arm of the A-shaped frame, and the roller supporting bars being provided with bearings, quilting rollers having trunnions at the ends thereof which are loosely received within the bearings, keepers upon one of the quilting rollers, and hook members upon the roller supporting bars for engagement with the said keepers.

In testimony whereof I have signed my name to this specification in the presence, 100 of two subscribing witnesses.

JOHN RUFF GLADNEY.
